UNITED STATES PATENT OFFICE.

ISAAC W. KNOWLES, JOHN N. TAYLOR, AND HOMER S. KNOWLES, OF EAST LIVERPOOL, OHIO.

DESIGN FOR A NAPPY OR DISH.

SPECIFICATION forming part of Design No. 15,753, dated January 27, 1885.

Application filed December 11, 1884. Term of patent 3½ years.

To all whom it may concern:

Be it known that we, ISAAC W. KNOWLES, JOHN N. TAYLOR, and HOMER S. KNOWLES, citizens of the United States, residing at East 5 Liverpool, in the county of Columbiana and State of Ohio, have invented and produced a new and original Design for Nappies, of which the following is a specification, reference being had therein to the accompanying 10 drawings.

Our design relates to dishes or "nappies" for table and other uses.

Figure 1 is a view in perspective of our design. Fig. 2 is a top or plan view. Fig. 3 is 15 a sectional view on the line $z-z$ of Fig. 2.

The body of the dish or nappy A, when viewed in plan, is square, with slightly rounded corners b at the top. The sides of the dish or nappy are slightly rounded or convex, and 20 taper from the top edge or rim to the base, the rim or edge having scallops a , which extend down the sides of the dish or nappy and form

flutes B. The indentations which form the flutes B are deeper or more marked at the rim or upper edge of the nappy than they are 25 at the bottom, so that the flutes gradually decrease from the top toward the bottom of the nappy. The interior of the dish or nappy is perfectly smooth and even, and, as before stated, is square, or practically so, in cross- 30 section.

What we claim, and desire to secure by Letters Patent, is—

A design for a nappy, consisting of a square dish having scalloped edges and fluted sides, 35 as set forth.

In testimony whereof we affix our signatures in presence of two witnesses.

ISAAC W. KNOWLES.
JNO. N. TAYLOR.
HOMER S. KNOWLES.
